UNITED STATES. PATENT OFFICE.

ERNESTO ABBIATI, OF NEW YORK, N. Y.

CLOTHES-LINE FASTENER.

SPECIFICATION forming part of Letters Patent No. 449,099, dated March 31, 1891.

Application filed September 30, 1890. Serial No. 366,642. (No model.)

To all whom it may concern:

Be it known that I, ERNESTO ABBIATI, a resident of the city of New York, in the county and State of New York, have invented a 5 Clothes-Line Fastener, of which the following is a specification.

My improvement relates to an automatic locking device or clamp to be used in connection with a running clothes-line or other line. 10 My object is to provide a simple device whereby the tension in a running clothes-line may be instantly increased or diminished, and that will automatically lock itself. These objects I attain by means of the mechanism 15 illustrated by the accompanying drawings, and hereinafter described, wherein—

Figure 1 is a side view of the locking device or clamp as applied to a running clothes-line. Fig. 2 is an enlarged side view of the 20 clamp, partly in section. Fig. 3 is a plan view of the clamp. Fig. 4 is a cross-section of the frame on the section-line *c c*, Fig. 3.

A is the slotted body or frame, constructed to allow the introduction of the pulley B and 25 the eccentric D, which is provided with a rounded face, which face has several transverse grooves, or is otherwise roughened, so that it will present a rough contact-surface. The pulley and eccentric are both held in 30 place so as to be free to turn by means of pins or gudgeons.

E is a handle or pin extending from the eccentric D.

G is a loop of wire or rope attached to the 35 end of the body or frame A.

In using this device one end of the clothes-line H is secured to the eccentric D, as indicated in Fig. 2. The line H is then laid over

pulleys M N, that are carried by stationary supports, and is finally carried over the pulley B between the same and the eccentric D, as shown in Figs. 1 and 2. The loop G may carry an eye F, through which the rope H is passed, but with such freedom as to allow rope H to slide easily. This eye F holds the frame in a position parallel to the rope H, which insures quicker action of the eccentric D. As the tension on the rope H increases, its tendency will be to draw the eccentric D around in the direction indicated by arrow 1 40 until, as the radius of the cam increases, the rope will become jammed and held between the face of the eccentric and the pulley B. By means of the handle E the cam can be thrown back, thus disengaging the rope, whereupon the desired tension can be made, the handle E released, and the cam D again automatically thrown against the rope to bind the same. 45

I do not desire to limit myself to fastening the rope H to the eccentric D by threading through a hole in eccentric, for it may be fastened to a screw-eye in said eccentric; but the said rope should connect with the eccentric to move the same into the binding position. 50

Having described my invention, what I claim is—

The combination of the frame A, having loop G, with the pulley B, eccentric D, and rope H, which is secured to said eccentric, said 55 loop G connecting with the rope by eye F, as set forth.

ERNESTO ABBIATI.
